[57] CLAIM

The ornamental design for a door assembly for wood stoves, as shown.

DESCRIPTION

FIG. 1 is a front elevational view of a door assembly for wood stoves, showing my new design;

FIG. 2 is a left side elevational view thereof;

FIG. 3 is a right side elevational view thereof;

FIG. 4 is a top plan view thereof;

FIG. 5 is a sectional view taken along line 5—5 of FIG. 3;

FIG. 6 is a bottom plan view thereof;

FIG. 7 is a sectional view taken along line 7—7 of FIG. 6;

FIG. 8 is a front elevational view of the base plate portion of the door assembly;

FIG. 9 is a rear elevational view of the door assembly of FIG. 1.

Aside from the rear ridge of the base plate, shown in FIGS. 4—7, the rear of the door assembly is essentially unadorned.
